CARTRIDGE-FUSE.

1,135,010.

Specification of Letters Patent.

Patented Apr. 13, 1915.

Application filed March 27, 1914. Serial No. 827,581.

To all whom it may concern:

Be it known that we, WILLIAM THOMAS GARLITZ and WILLIAM ROWLES GARDNER, citizens of the United States of America, residing at McKees Rocks, in the county of Allegheny and State of Pennsylvania, have invented certain new and useful Improvements in Cartridge-Fuses, of which the following is a specification, reference being had

10 therein to the accompanying drawing.

This invention relates to cartridge fuses, and has for its object to provide a fuse of such class, in a manner as hereinafter set forth, to enable the quick refilling of the

15 same when occasion so requires.

A further object of the invention is to provide a fuse of such class, with means in a manner as hereinafter set forth, for setting up a positive and rapid clamping device for the fuse link.

A further object of the invention is to provide a cartridge fuse with means as herein-after set forth, for simultaneously binding the fuse link with the locking of the end cap to the shell of the fuse.

A further object of the invention is to provide a refillable cartridge fuse with means, in a manner as hereinafter set forth, for centering the fuse link quickly with respect

30 to the shell and caps when refilling the fuse.

A further object of the invention is to provide a refillable cartridge fuse, in a manner as hereinafter referred to, overcoming the inconvenience of contending with loose parts

35 when the fuse link is removed and a new one substituted, thus eliminating any possibility of losing or misplacing any of the elements of the fuse during the act of re-filling.

40 A further object of the invention is to provide a refillable cartridge fuse, with means in a manner as hereinafter set forth, for locking the cap firmly to the shell and to further permit of the quick removal of the cap when desired.

A further object of the invention is to provide a cartridge fuse, with means in a manner as hereinafter set forth, for ventilating the shell when occasion so requires.

50 A further object of the invention is to provide a refillable cartridge fuse including a pair of caps carrying means for clamping the fuse link in position, the said means being permanently carried by the caps when these latter are connected to or removed

from the shell, and the said means further constitute locks for securing the caps to the ends of the shell.

A further object of the invention is to provide a cartridge fuse, with means for permanently holding the fuse link in position for the purpose of forming a perfect electric contact irrespective of the contraction or expansion of the shell.

A further object of the invention is to provide a cartridge fuse, with means to overcome the causing of loose contact between the fuse link and caps due to the shrinking of the shell.

Further objects of the invention are to provide a quick refillable cartridge fuse, which is simple in its construction and arrangement, strong, durable, efficient and convenient in its use, readily set up, and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings, wherein like reference characters denote corresponding parts throughout the several views: Figure 1 is a longitudinal sectional view of a cartridge fuse in accordance with this invention, Fig. 2 is a bottom plan partly broken away and partly in section, Fig. 3 is a perspective view broken away, illustrating one end of the shell, and Fig. 4 is a transverse sectional view through one of the end caps.

Referring to the drawings in detail, 5 denotes a cylindrical shell formed of insulation, preferably fiber, and said shell 5 near one end is provided with a circular opening 6, and projecting from each opening 100 6 and terminating at an end edge is a longitudinally extending slot 7 of a width less than the diameter of its respective opening. The openings 6 are arranged in longitudinal alinement, as well as the slot 7, but these latter extend in opposite directions with respect to each other.

Mounted upon each end of the shell is a cap formed of conducting material, and as the construction of each cap is similar, but

one will be described, as the description of one applies to the other. Each cap consists of a body portion 8 having projecting from its outer face a flat extension 9 and the said body portion 8 has projecting inwardly therefrom a rim 10 which is seated upon the periphery of the shell 5, and when in such position, one end of said shell 5 abuts against the inner face of the body portion 8. The inner face of the body portion 8 is recessed as at 11, to provide a seat for a purpose to be presently referred to. The body portion 8 is furthermore provided with one or more openings 12, for the purpose of ventilating the shell 5, for example allowing of the escape of any gases which are generated within the shell 5. The rim 10 is provided with an opening 13, and is furthermore provided diametrically opposite the opening 13, with an opening 14, the latter having its wall screw threaded. The opening 13 is of greater diameter than the opening 14 and the purposes for which the said openings 13 and 14 are intended will be presently referred to. Carried by the body portion 8, and projecting inwardly therefrom is a guide member which consists of a body portion 15 having one end formed with a right angularly disposed flange 17, which is positioned against the seat 11 and secured to the body portion 8 of the cap through the medium of a holdfast device 18, the latter being illustrated as a screw and which has its head countersunk in the outer face of the body portion 8. The body portion 15 of the guide member has its other end formed with an upwardly projecting curved lip 19. The body portion 15 is formed with a centrally disposed opening 20 having the wall thereof threaded and the function of said opening 20 will be presently referred to.

Associated with the guide member 15 for the purpose of clamping one end of a fuse link 21 in position is a washer or supporting member 22, which opposes the guide member 15, and which is carried by a transversely extending clamping screw, the latter in connection with the threaded openings 14 and 20 not only clamps one end of the fuse link 21 to the guide member 15, but also locks the cap to the shell 5. The clamping screw includes a head 23 and a shank formed of two lengths of different diameters, that length of larger diameter is indicated at 24 and that length of smaller diameter at 25. The length of larger diameter is formed integral with the head 23 and is of less diameter than said head 23, but of such diameter as to permit the passage of such length 24 through the slot 7. The length 24 of the shank of the clamping screw is plane, while the length 25 is peripherally threaded from end to end. At the point of mergence of the length 25 and the length 24 of the shank of the clamping screw, a shoulder 26 is pro-

vided upon which is mounted the washer or supporting member 22 constituting a fuse clamp. The washer 22 loosely surrounds the length 25 of the shank. The shell 5 is provided with openings 27, which register with the openings 14, when the caps are mounted upon the ends of the shell 5. The fuse link 21, has each end enlarged as at 28, and which is bifurcated as at 29, to enable the said ends to be extended between the members 19 and 22, as the bifurcated ends 29 provide clearances for the lengths 25 of the clamping screws when the fuse link is positioned through the medium of the clamping screws to the caps. When the clamping screws are in position to secure the fuse link 21 to the caps, the heads 23 extend into the openings 6 and 13 and the threaded lengths 25 of the clamping screws engage the threaded walls of the opening 14, as clearly illustrated in Fig. 1.

From the foregoing construction and arrangement of parts, it is obvious that when the caps are detached from the shell 5, the clamping screws, washers, and guide members are carried with the caps, or in other words, it is not necessary to disconnect the clamping screws, washers or guide members from the caps when these latter are detached from the shell, and by such an arrangement, there is no possibility of losing or misplacing any of the elements referred to.

The members 19 are employed for quickly guiding or positioning the ends of the fuse link 21 with respect to the washers 22 and clamping screws 25, and said members quickly center the fuse link longitudinally of the casing. As the connecting of the fuse link 21 longitudinally of the shell 5 is had directly with the cap, it is obvious that it will always remain in position irrespective of the shrinkage or expansion of the shell.

To remove a cap, a clamping screw is detached from engagement with the threads of the wall of an opening 14, and shifted clear of an opening 27, such movement on the part of the clamping screw will position the head 23 clear of the opening 6, under such conditions the length 24 of the shank of the clamping screw can be passed outwardly through the slot 7, under such conditions the cap is then detached from the shell. When the cap is detached from the shell, the clamping screw, washer and guide member are carried with the cap as these elements are permanently connected to the cap.

The openings 27 are of greater diameter than the threaded lengths 25 of the clamping screws and the openings 6 are of greater diameter than the heads 23 of the clamping screws, and by such an arrangement contraction and expansion of the shell 5 is provided for. By providing the openings 6 of greater diameter than the heads 23 and the openings 27 of greater diameter than the

threaded lengths 25 of the shanks of the clamping screws, a slight movement of the caps can be had so that the extensions or blades 9 will adjust themselves when placing them in engagement with the clips on the fuse blocks, and under such conditions making the blades 9 what may be termed self alining.

What we claim is:—

1. A cartridge fuse comprising a shell, caps mounted upon the ends thereof, guide members carried by the caps and projecting into the shell, transversely extending shoudered clamping screws engaging in the caps at two points and extending entirely through the shell for connecting the caps and shell together, and fuse clamping members having said screws extending therethrough and capable of being shifted by the shoulders of the screws for clamping the ends of the fuse to said guide members, said screws extending through and engaging with said members.

2. A cartridge fuse comprising a shell having its ends provided with openings and longitudinal slots of less diameter than said openings leading from some of said openings to the termini of the shells, caps mounted on the ends of the shell and having openings registering with the openings of the shell, transversely-extending shiftable elements provided with heads, the heads of said elements seated in the registering openings, one of which communicates with the slot and further extending through the shell and engaging in the other of said registering openings whereby the caps are connected to the shell, and means engaged by said headed elements for electrically connecting the ends of a fuse with said caps, said slots being of a diameter substantially equal to the diameter of the transversely-shiftable elements and providing for the removal of said caps from said shell without disconnecting said headed elements from said means when said heads are shifted exteriorly of the caps and free of the openings.

3. A cartridge fuse comprising a shell, a cap mounted on one end thereof, a guide member carried by the cap, a transverse clamping screw engaging in the cap at two points and extending entirely through the shell for connecting the cap thereto, said screw having a shoulder, a fuse clamping member having said screw extending therethrough and capable of being shifted by said shoulder for clamping the end of a fuse to said member, said screw extending through the latter, and means for clamping the other end of the fuse to the other end of the shell.

4. A cartridge fuse comprising a shell, a cap mounted on one end thereof, a member carried by the cap, a transverse clamping element engaging in the cap at two points

and extending entirely through the shell for connecting the cap thereto, said element having a shoulder, a fuse clamp having said element extending therethrough and capable of being shifted by said shoulder for clamping the end of a fuse to said member, said element extending through the latter, and means for clamping the other end of the fuse to the other end of the shell.

5. A cartridge fuse comprising a shell, a cap mounted on each end thereof and carrying an inwardly extending guide member, a clamping member associated with said guide member, a transverse element for supporting said clamping member, said transverse element having threaded engagement with said guide member and further engaging with said clamping member for clamping one end of a fuse to the cap, said transverse element extending completely through the cap and shell, and means for clamping the other end of the fuse to the other end of the shell.

6. A cartridge fuse comprising a shell, a cap mounted on one end thereof, a guide member carried by the cap, a transverse headed clamping element extending through and engaging with said guide member, a fuse clamp associated with said guide member and bodily carried by said clamping element, and said element having means spaced from the head thereof adapted for engaging with said clamp for shifting it to clamp one end of a fuse to said guide member, and means for clamping the other end of the fuse to the other end of the shell.

7. A cartridge fuse comprising a shell, a cap mounted on each end of the shell, guide members carried by the caps, said shell and caps having diametrically-disposed registering openings, one of the shell openings at each end thereof communicating with a slot that opens at the end of the shell and which slot is of less diameter than said opening, a headed element extending transversely of said shell ends with the head thereof received in said slotted opening, clamping members supported on said headed elements, the opposite end of each transversely-extending element passing through the guide member and clamp and threaded into the shell and cap to prevent withdrawal of the cap, each of said elements adapted to be shifted axially to remove the head thereof from said opening and to permit the opposite end to clear the inner surface of the shell, whereby the cap may be moved outwardly with the transversely-extending element passing through the slot.

8. A cartridge fuse comprising a shell, caps having diametrically disposed openings therein mounted on the ends thereof, each end of the shell having diametrically-disposed openings adapted to register with the openings in the caps, one of which openings

4 at each end communicates with a slot of reduced diameter opening at the ends of the shell, a headed screw member extending transversely of said shell ends and received in said openings with the head thereof disposed in the opening communicating with the slot, a fuse supported at each end on said screw members, means carried by the caps through which the screws extend, and means controlled by said screws adapted to positively engage the fuse ends, said screw head

adapted to be removed from said opening with the opposite end clear of the inner surface of the shell to permit the caps and screws to be removed from the shell.

15

In testimony whereof we affix our signatures in the presence of two witnesses.
